BLOW-OFF APPARATUS FOR LOCOMOTIVE BOILERS

Walter H. Hinsch, Chicago, Ill., assignor to Dearborn Chemical Company, Chicago, Ill., a corporation of Illinois

Application July 20, 1936, Serial No. 91,510

5 Claims. (Cl. 122—382)

This invention relates to improvements in blow-off apparatus for locomotive boilers and it consists of the matters hereinafter described and more particularly pointed out in the appended 5 claims.

One of the objects of the present invention is to provide a blow-off apparatus for locomotive boilers operative continuously to discharge boiler water after the throttle lever has been opened 10 to and beyond a certain position approximating "drifting" speed for the locomotive.

A further object of the invention is to provide in a blow-off apparatus of this kind an improved self-closing trip valve and operating means 15 therefor associated with the throttle lever, whereby said valve may be easily actuated and chattering prevented when open.

The above mentioned objects of the invention, as well as others, will more fully appear as the 20 specification proceeds.

In the drawings:

Fig. 1 is a view in side elevation of a blow-off apparatus embodying the invention as applied to a locomotive boiler and associated parts, the latter appearing in dotted lines;

Fig. 2 is a view in end elevation of the parts appearing in Fig. 1;

Fig. 3 is a view in side elevation on an enlarged scale of parts associated with the throttle valve 30 for operating the trip valve;

Fig. 4 is a plan view of parts appearing in Fig. 3;

Fig. 5 is a vertical sectional view through the trip valve of the apparatus on an enlarged scale 35 as taken on the line 5—5 of Fig. 3;

Fig. 6 is a top plan view of the blow-off valve also on an enlarged scale;

Fig. 7 is a view in side elevation of the blow-off valve, with parts broken away better to illustrate 40 internal parts thereof, as will later appear;

Fig. 8 is a vertical sectional view through a part of the blow-off valve as taken on the line 8—8 of Fig. 7, and

Fig. 9 is a vertical sectional view through another part of the blow-off valve as taken on the line 9—9 of Fig. 7.

Referring now in detail to that embodiment of the invention illustrated in the drawings, 10 indicates as a whole a locomotive having a boiler 11 including a firebox 12, side water legs 13 and a rear water leg 14. The cab of the locomotive is indicated at 15 and the ashpan is indicated at 16. All of these parts are arranged in the conventional manner.

55 In the cab of the locomotive, the throttle lever

17 is located, pivoted at 17a to a bracket 18 on the boiler shell and which bracket also supports the associated quadrant 19. The throttle lever carries a latch 20 and latch lever 21. Through these parts, the throttle lever may be locked 5 in the position giving the desired throttle opening. The lever 17 includes an arm 22 to which one end of the throttle rod or stem 23 is operatively connected, sliding through the bracket 18 and leading to the throttle valve (not shown). 10 When the lever 17, which as herein shown, is arranged substantially in a vertical plane, is swung in one direction or the other, the throttle valve is opened or closed in the manner well known.

Attached to the throttle lever bracket is a second bracket 24 for supporting a trip valve 25. Said valve includes a hollow valve body 26 with opposed inlet and outlet ends 27—28 and opposed but aligned threaded extensions 29 and 30 respectively, disposed in a plane at a right angle 20 to the inlet and outlet ends. In the hollow body between the inlet and outlet ends is a partition 31 in which is secured a ring 32 formed to provide a tapered seat associated with the inlet side of the valve body. The valve body 26 is 25 disposed with its inlet and outlet ends arranged in a vertical plane, with the inlet end uppermost. The threaded extension 29 passes through a suitable hole in the bracket 24 and a nut 33 is provided on said extension to clamp against said 30 bracket to secure the valve in position with respect to said bracket.

34 indicates the tapered valve member of the trip valve which is adapted to engage the tapered seat in the ring 32. This valve member includes 35 a stem 35 having sliding guided engagement in a cap 36 secured to the extension 30 by a nut 37. A washer 38 is associated with the valve member 34 and a helical extension spring 38a is interposed between said washer and the cap 36 40 normally to hold the valve member closed upon its seat.

Slidable in the extension 29 of the valve body 26, is a valve operating stem or spindle 39 having an inner end of reduced diameter engaged with 45 the valve member 34. Mounted on the stem is a packing box gland 40 coacting with packing material 41 in a cavity in the extension 29. A nut 42 is threaded on the extension 29 and between the nut and gland is a spring 43. By means of 50 the nut, the tension of the spring and resultant pressure on the packing material 41 may be controlled. This reduces the friction around the spindle and provides for ease in operation. When the spindle is depressed inwardly of the valve 55

extension, it forces the valve member 34 off its seat against the action of the spring 38a and opens the valve. Upon the release of pressure upon the valve spindle, the spring 38a operates 5 to close the valve. Thus the trip valve is a self-closing one.

The inlet end 27 of the valve is connected by a steam line 44 to the turret (not shown) of the boiler and in this line is a valve 45 (see Fig. 1) 10 for controlling the passage of steam therethrough. The outlet end 28 of said valve is connected by a line 44a to a blow-off valve hereinafter described.

The trip valve is adapted to be opened and closed in timed relation with respect to certain 15 positions of the throttle lever 17. To accomplish the opening of the trip valve, a lever-like arm 46 is employed. The arm is provided at a point between its ends with a plurality of longitudinally spaced holes 46a. A pin 47 may be passed 20 through the desired hole and through apertured ears 24a (see Fig. 4) on the bracket 24 to pivotally connect the arm to the bracket. When the arm is thus mounted on the bracket, one end of said arm engages the end of 25 the spindle or stem 39 of the trip valve. The extremity of said end has guided engagement between said lugs 24b on said bracket.

The other end of said arm is disposed in close 30 proximity to the plane of the throttle lever 17 and about midway of said end is carried a roller 48. When the throttle lever is swung into a position to open the throttle, it engages the roller and swings the arm end laterally outward. This 35 swings the other end of said arm laterally inward and depresses the valve spindle 39 to open the trip valve. The roller 48 is so located with respect to the throttle lever as to permit actuation of the throttle to "drifting" speeds for the locomotive, without engaging the roller so that the trip valve remains closed at such speeds. By reason of the plurality of holes 46a in said arm, the arm may be adjusted longitudinally with respect to the bracket 24 to set the roller 48 to give the desired adjustment for opening the trip valve at the proper position of the throttle lever 17. When 40 the throttle lever is actuated to open the throttle to a position wherein the locomotive is working steam, it will engage the roller in the arm to open the trip valve and will hold the arm in a position holding the trip valve open.

50 When the throttle lever is swung in the other direction to "drifting" speed or "off", the pressure on the trip valve spindle is released and the valve closes under the action of the spring 38a in said valve. By reason of the use of the roller, an antifriction engagement is provided between the throttle lever 17 and arm 46 at the time when the resistance of opening the trip valve is imposed upon the throttle lever. Therefore the 55 throttle lever is easier to manipulate for its intended purpose when the trip valve is to be opened.

As before stated, the line 44a leading from the 60 outlet end or side of the trip valve is connected to an automatic blow-off valve and which valve is herein indicated as a whole by the numeral 52. This valve is disposed near the rear bottom 65 end corner of the right hand side water leg of the boiler. It comprises a one piece casing or hollow body in which is formed chamber 51, the body having a hollow lateral extension 52 that terminates in a bolting flange 53 carrying a joint ring 54. This ring is adapted to engage in a suitable hole 55 in the outer sheet of the associated side water leg and bolts 56 pass through 70 75

the flange into said sheet to secure the casing in pressure-tight relation with respect to the boiler as a whole.

The hollow extension defines a passage 57 and the inner end of said passage is separated from a 5 part of the chamber 51 by a partition 58. Engaged in said partition is a valve seat ring 59. Axially in line with said ring, the casing is provided with an upright tubular extension 60 upon which is threaded a union nut 61 to secure a 10 stuffing box sleeve 62 in place upon said extension. A valve stem 63 has a threaded engagement in 15 said sleeve and carries a head 64 at its bottom end for engagement on the seat as provided by the valve ring 59. The top end of the sleeve 62 carries a stuffing box arrangement 65 through 20 which the stem 63 extends, the extremity of said stem outside the arrangement mentioned, being squared to receive a wrench or other operating member. When the valve head is engaged on the 25 ring seat, communication between the passage 57 and chamber 51 is shut off so that no boiler water can pass into said chamber from the boiler. When said valve head is off said seat, the said 30 passage and the said chamber are brought into communication with each other so that boiler water may pass into said chamber.

The body of the valve casing is further formed with an upright tubular boss 66 which is closed at its top and bottom ends by screw caps or plugs 66 and 67, respectively. The vertical axis of said boss is offset inwardly from the horizontal axis of the chamber 51. In the bottom end of the boss a chamber 68 is formed and in that wall of the casing body separating the chamber 68 from the 35 chamber 51 an orifice nipple 69 is threaded. This nipple which controls the amount or volume of boiler water passing through the blow-off valve when open, has a projectile type of nose arranged in the chamber 51 to prevent the closure of the 40 orifice by accumulation of foreign particles such as boiler scale. That end of the chamber 51 opposite the orifice nipple is closed by a screw cap or plug 70 of such size as to permit access to the 45 nipple for removal in changing or replacing the same. In the bottom of that part of the casing body defining the chamber 51 is a drain cock 71 for draining the chamber. This cock permits of 50 a convenient drawing off of a more representative sample of the boiler water. The nipple 69 is so disposed that its orifice opens tangentially 55 into the chamber 68 in the bottom of the boss 66.

Threaded into the boss 65, is a cylinder sleeve 72 with a tapered seat 73, and a valve seat ring 74 spaced apart by a chamber 75. The ring 74 defines a downwardly facing seat against which a spherical valve member 76 is normally held by a spring 77 carried by the plug or cap 67. It is to be noted from Fig. 9 that the orifice nozzle 69 discharges its jet tangentially into the chamber 68 so as to scour the walls thereof to keep them 60 free of accumulation of scale or the like. With the tangential arrangement mentioned, another 65 advantage is present in that the jet from the orifice nozzle does not discharge upon the valve member 76 or its seat to pit or otherwise damage them.

78 indicates a piston which operates in the sleeve 72 and the bottom end of said piston is bevelled to have a tight seating engagement on the 70 seat 73 when the piston has been moved downwardly as will later appear. The line 44a before mentioned, opens laterally into the top end of the boss 65 above the piston 78 therein. In the piston 75 is a small port 79 for releasing the steam from

the blow-off valve cylinder and the line 44a feeding it when the trip valve 25 is closed.

The piston is provided with a bottom end pin-like stem 80 for engagement with the ball valve member 76. When the piston is moved downwardly said valve member is pushed off its seat against the action of the spring 77 to open communication between the chambers 68 and 75, the latter chamber being the one from which boiler water is discharged as will soon appear. The piston is further provided with a top end guide extension 81 which slides in a guide recess 82 provided therefor in the top cap or plug 66. In said extension 81 is a small groove 83 through which steam may bleed to prevent the formation of a vacuous condition in said recess effecting the operation of the piston.

Threaded into the boss 65 in communication with the chamber 75 is one end of the discharge pipe 84 for the blow-off valve as a whole. This pipe leads to a steam separator indicated as a whole as at 85 and which is carried upon a part of the side frame of the locomotive adjacent the ashpan 16 (see Fig. 2). This separator includes a hollow cylindrical body 86 closed by suitable top and bottom heads 87 and 88 respectively. Within the body and supported by and depending coaxially from the head 87 is a tubular skirt 89.

Opening tangentially into the top and bottom ends of the body 86 and facing in opposite directions are water inlet and outlet nipples 90 and 91 respectively, the pipe 84 before mentioned, being connected to the inlet nipple 90. A drain pipe 92 is connected to the nipple 91 for conducting water from the separator to discharge upon the road bed.

A steam conducting pipe 93 leads from the axis of the head 87 and is so formed as to discharge steam into the ashpan.

The operation of the blow-off apparatus above described is as follows:

When the throttle lever 17 is in its "off" position, wherein the associated throttle valve is closed, it is apparent that the lever is out of engagement with the arm 46 so that the trip valve is closed. When the trip valve is thus closed, the blow-off valve is likewise closed. Assume, however, that the valve 45 in the line 44 is open and that the shut-off valve 63-64 of the blow-off valve, as a whole, is in its normally open condition.

When the throttle lever is swung clockwise as in Fig. 1, it starts opening the throttle for delivery of steam to the locomotive driving cylinders. The initial movement of said lever produces the slow or drifting speeds for the locomotive. As the lever passes beyond this point, it engages the roller 48 in the long arm of the lever 46 and pushes the same outward, causing the shorter end of the arm to swing inward. As this last mentioned end of the arm is engaged with the spindle 39 of the trip valve, it depresses the same and this pushes the valve member 34 off its seat against the action of the spring 38a. Steam under boiler pressure then enters the trip valve 25 from its inlet end or side 27 to pass through the valve ring 32 to the outlet end or side 28 and into the line 44a. As said line is connected to the blow-off valve, steam under boiler pressure enters into that space in the hollow boss 65 between the cylinder sleeve 72 and cap or plug 66 to build up a pressure on the top side of the piston 78. This forces the piston downwardly until its beveled bottom end engages the seat 73 in the sleeve 72. Due to the provision of the small groove 83 in the extension 81 of the piston, steam enters into

the recess 82 above said extension and this prevents the formation of any vacuous condition in said recess to exert a holding back action on said extension and its piston.

In the downward movement of the piston, its stem 80 forces the ball valve 76 downwardly off its seats in the ring 74. The blow-off valve is now open so that boiler water in the right hand side water leg, under boiler steam pressure, enters the passage 57. From said passage, said water passes through the valve seat ring 59 into the chamber 51 and then passes through the orifice in the nozzle 69 for discharge as a continuous jet, tangentially into the chamber 68 in the bottom end of the valve boss 65. Due to the entrance of the jet tangentially into said chamber, it cannot impinge upon the ball valve but acts to scour the walls of said chamber clean.

As the valve member 76 is being held off its seat by the piston stem 80, the water passes through the valve ring 74 into the chamber 75. Due to the differential in areas of the ends of the piston 78, the pressure of the water in said chamber is ineffective to lift the piston, so that the water passes out through said chamber 75 into the pipe 84. This water is conducted to the inlet end of the separator 85 and due to its pressure release therein, a part is generated into steam. Such water as enters the separator follows around the inside of its casing wall with a centrifugal action, thus forcing the steam inwardly to pass under the skirt 89 therein for a discharge out through the pipe 93 into the ashpan 16 beneath the grates of the firebox. As the water passing around the inside of the separator 85 approaches the bottom end thereof, if it enters the drain pipe 92 for wayside discharge.

It is to be borne in mind that the trip valve 25 is held open by reason of the engagement of the throttle lever with the arm 46 at all speeds beyond locomotive "drifting" speed, and this in turn holds the blow-off valve constantly open. Thus there is a continuous blow-off or discharge of foul boiler water, the volume of which is controlled by the diameter of the orifice in the nozzle 69 of the blow-off valve.

The continuous passage of boiler water through the nozzle orifice mentioned, produces a wear thereon which enlarges the diameter of said orifice. This, of course, increases the volume of discharge to one above the desired volume. To remedy this condition, requires the replacement of the worn nozzle by a new one.

With the locomotive under steam but with the throttle closed, the valve stem 63 is manipulated to cause its head 64 to engage on the seat of the ring 59 and this closes off the blow-off valve. The plug 70 at the end of the chamber 51 is then removed to give access to the nozzle 69. By means of a suitable socket wrench the worn orifice nozzle 69 is unscrewed and removed and a new one with a proper size orifice is substituted. At this time, the chamber 51 may be cleaned out to rid it of any scale and like accumulation and the plug 70 is then replaced. Thus it is apparent that the nozzle may be removed and a new one substituted therefor without a shut-down of the locomotive. The apparatus may be made ready for future operation merely by opening the shut-off valve 63-64 to provide communication between the passage 57 and chamber 51.

It is apparent that with the construction described, parts of the blow-off valve may be readily removed and replaced without requiring boiler 75

shut-down and without removing the blow-off valve or injuring the same.

The roller arrangement on the trip valve arm, reduces friction against the throttle lever. This makes the throttle lever easier to operate and it also makes the trip action of the valve more rapid and reduces the tendency to wire draw.

While in describing the invention, I have referred in detail to the form, arrangement and construction of the various parts thereof, the same is to be considered only in the illustrative sense so that I do not wish to be limited thereto except as may be specifically set forth in the appended claims.

15 I claim as my invention:

1. A continuous blow-off apparatus for locomotive boiler embodying therein a member for actuating a steam throttle for the main cylinders of the locomotive, a blow-off valve including pressure responsive means, a steam line connected to the boiler and to the pressure responsive means of the blow-off valve respectively, for actuating the latter, a trip valve in said steam line for controlling passage of steam to the blow-off valve, a member for opening the trip valve and having a portion so disposed as to be engaged by and actuated in the movement of said first mentioned member beyond a predetermined position thereof, one of said members including an anti-friction roller for engagement by the other in the movement of said first mentioned member to said predetermined position.

2. A continuous blow-off apparatus for locomotive boiler embodying therein a member for actuating a steam throttle for the main engine cylinders of the locomotive, a blow-off valve including pressure responsive means, a steam line connected to the boiler and to the pressure responsive means of the blow-off valve respectively, for actuating the latter, a trip valve in said steam line for controlling passage of steam to the blow-off valve, and a member for opening the trip valve and carrying a roller adapted to be engaged by said first mentioned member in its movement into said first mentioned position to cause it to impart an opening movement to the trip valve.

3. In a blow-off apparatus for locomotive boilers, a steam line leading from the boiler, a trip valve in said line and including a normally closed spring pressed valve stem, a throttle lever for the main engine cylinders of the locomotive

pivotedly mounted for movement from throttle closing position to throttle opening position, means cooperating with the throttle lever for holding it in any of its positions, a trip valve actuating lever pivoted at a point between its ends 5 and operatively engaged at one end with said valve stem and having its other end arranged adjacent the plane of the movement of the throttle lever, and means on one of said levers operating in the swinging movement of the throttle lever at 10 a point between throttle closing and throttle opening positions to engage said other end of the trip valve actuating lever to cause its first mentioned end to depress the stem of the trip valve to open the same.

4. In a blow-off apparatus for locomotive boilers, a steam line leading from the boiler, a trip valve in said line and including a normally closed spring pressed valve stem, a throttle lever for the main engine cylinders of the locomotive pivotally mounted for movement from throttle closing position to throttle opening position, means cooperating with the throttle lever for holding it in any of its positions, a trip valve actuating lever, means providing an adjustably pivotal mounting 20 for the mid portion of said trip valve actuating lever with respect to said trip valve stem, said lever including an arm engaged with said valve stem and a second arm with a portion arranged adjacent the plane of the movement of the 25 throttle lever, and means on one of said levers operating in the swinging movement of the throttle lever at a point between throttle closing and throttle opening positions to engage said second arm to cause the first mentioned arm to depress the valve stem to open the trip valve.

5. In a blow-off apparatus for locomotive boilers, a steam line leading from the boiler, a trip valve in said line and including a normally closed spring pressed valve stem, a throttle lever for the main engine cylinders of the locomotive pivotally mounted for movement from throttle closing position to throttle opening position, means cooperating with the throttle lever for holding it in any of its positions, and a roller carried by the 40 other end of the trip valve actuating lever and engageable by said throttle for causing the first mentioned end of said trip valve actuating lever to depress said valve stem to open the trip valve.

50 WALTER H. HINSCH.
